UNITED STATES PATENT OFFICE.

WILLIAM M. SCOTT, OF TREDYFFRIN TOWNSHIP, CHESTER COUNTY, PENNSYLVANIA.

SWITCHING APPARATUS.

Application filed August 2, 1923. Serial No. 655,196.

My invention relates to electrical switch or circuit breaker structure for controlling or protecting electric circuits carrying current for power, lighting or other purposes.

5 In accordance with my invention, switch or circuit breaker structure is provided with means for restoring or resetting it to normal, generally circuit closing, position, in combination with means for locking the restoring or resetting means against actuation, operable by the application of a separable or removable locking device, as a padlock.

Further in accordance with my invention, there is combined with the locking means 15 for the restoring or resetting mechanism means for tripping the switch or circuit breaker mechanism actuated simultaneously with movement of the locking means to locking position, whereby the switch or circuit 20 breaker mechanism is tripped at or before the time the restoring or resetting mechanism is locked, to the end that the switch or circuit breaker structure shall be in open circuit position during the time the resetting mechanism is locked against operation.

Further in accordance with my invention, the aforesaid locking means, or said locking means and tripping mechanism, are applied 30 to the resetting mechanism carried by and operable from the exterior of a housing which encloses the switch or circuit breaker structure.

My invention resides in features of structure, arrangement and combination herein-after described and claimed.

For an illustration of some of the various forms my invention may take, reference is to be had to the accompanying drawings, in 40 which:

Fig. 1 is a side elevational view, partially in vertical section, of apparatus embodying my invention.

Fig. 2 is a front elevational view of structure shown in Fig. 1, with parts of the housing broken away.

Fig. 3 is a fragmentary side elevational view, partly in vertical section, of the resetting, locking and tripping mechanism of the character illustrated in Fig. 1.

Figs. 4 and 5 are, respectively, side and front elevational views of the actuating member for the resetting mechanism.

Figs. 6 and 7 are, respectively, side and

front elevational views of members co-acting 55 with the actuating member of Figs. 4 and 5.

Figs. 8 and 9 are, respectively, side and front elevational views of one of the members comprised in the locking and tripping 60 structure.

Figs. 10 and 11 are, respectively, top plan 65 and front edge views of the locking member comprised with the member of Fig. 9 in the locking and tripping structure.

Figs. 12 and 13 are, respectively, side and front elevational views, on enlarged scale, of the assembled structure comprising the members of Figs. 5, 7, 9 and 10.

Fig. 14 is a fragmentary front elevational 70 view of the resetting mechanism in association with the operating members of the circuit breakers.

Fig. 15 is a fragmentary side elevational 75 view, some parts in vertical section, of a modified structure of resetting, locking and tripping mechanism.

Fig. 16 is a front elevation of the same.

Fig. 17 and 18 are, respectively, side and front elevational views of one of the members of Fig. 15.

Figs. 19 and 20 are, respectively, side and front elevational views of a further modification of the resetting, locking and tripping mechanisms.

Figs. 21 and 22 are, respectively, side and front elevations of one of the members utilized in the arrangement of Fig. 19.

Figs. 23 and 24 are, respectively, side and front elevational views of a further modification in which the locking of the resetting mechanism is effected without tripping the circuit breaker mechanism.

Figs. 25 and 26 are, respectively, side and front views of the locking member of the 95 structure of Fig. 23.

Fig. 27 is a fragmentary top plan view of structure for mounting the housed circuit breaker upon a switchboard.

Referring to the drawings, 1 is a base, 100 preferably of insulating material, such as slate, marble and the like, upon which are secured two switches or circuit breakers A and B, Fig. 2, arranged in a double arm system. Inasmuch as the switches or breakers A and B may be and preferably are similar, a description of one will suffice for both.

While my invention is applicable to relations other than indicated, it is here shown as applied to the two circuit breaker arms, A and B, forming a so-called "double arm" circuit breaker, the two arms or poles of which are independently operable to normal or circuit closing position, both connected in series in the same circuit, preferably in opposite sides of the circuit, with automatic tripping mechanism ensuring the tripping of an arm first closed if there obtains an overload or other abnormal electrical condition upon attempt to close the other arm, in general as described in my prior Letters Patent No. 1,389,996.

Each arm, switch or circuit breaker comprises the main terminals 2 and 3, adapted to be engaged and electrically bridged by the laminated bridging member 4 carried by the arm 5 pivoted at 6 to the bracket or housing 7 carried by the base 1. Pivoted to the arm 5 at 8 is the toggle member or link 9 pivoted at 10 to the second toggle link 11 pivoted at 12 to the bracket 7. The member 9 carries the pin or roller 13. Carried by the member 9 is the locking pin or roller 14 engaged by the hook latch 15 pivoted to the bracket 7 at 6, and having the tail 16 disposed in the path of travel of the latch actuator or bar 17 pivoted concentrically with the latch 15 and extending in front of both arms A and B of the circuit breaker mechanism, and having in each breaker arm the tail 18 disposed in the path of travel of the member 19, secured to the armature 20, pivoted at 21 in operative relation to the poles 22, 22 of an electro-magnet having the overload or other winding 23, whose one end connects with the lower main terminal 3 and whose other end connects with the stud 24, which extends through the base 1 and the switchboard S.

A similar stud 25 extends through the base 1 and switchboard S and connects with the upper main terminal block 2, whereby a supply circuit conductor connected to the stud 25 conducts current therethrough and through the terminal 2, bridging member 4, lower terminal 3, winding 23 to stud 24, with which may be connected a consumption circuit conductor.

Enclosing the switch or circuit breaker mechanism is the housing H, preferably of sheet metal, having the front wall W, upon whose inner side is secured the bracket-member 26 having at 27 and 28 bearings in which rotates a tubular or hollow shaft 29, to which is secured within the casing, in detached relation to the operating members 13, 13, the resetting member 30, rotatable in opposite directions for resetting or reclosing the switches or circuit breakers in succession. The shaft 29 extends to the exterior of the housing wall W, where there is secured thereto the actuator member or

block 31, carrying the operator's handle 32, of the resetting or reclosing structure or mechanism.

Pivoted to the inner end 26^a of the bracket 26, at 33, is a tripping lever or member 34 whose end is adapted to engage and actuate the bar 17 for actuating both latches 15 to trip both switches or circuit breakers. The shaft 29 at its left end, see particularly Fig. 3, is counter-bored to receive the helical spring 35, which at one end engages the tripping lever 34 and at its other end engages the head 36 of the plunger 37, which extends into the bore 38 in the shaft 29, longitudinally of which bore is movable the rod 39 carrying at its outer end, on a portion of reduced diameter, the button 40, whereby upon pushing the button 40 toward the left, Figs. 1 and 3, the rod 39 is moved toward the left, causing movement of the plunger 37 toward the left, thereby actuating the tripping lever 34 through the spring 35, in opposition to spring 41, connected at its one end to the tripping lever 34 and at its other end to the bracket 23. The spring 35, intervening between the tripping lever 34 and the rod 39, serves to protect the tripping lever and the associated tripping mechanism against shock in case the button 40 be struck a blow or otherwise violently actuated.

Secured by rivets 31^a to and embracing the actuator block 31 is the U-shaped member 42 having the sides 43, 43 and the transversely extending top member 44, the latter spaced from the top of the block 31 to provide a channel in which is movable the sliding locking member or plate 45, having the locking lug or projection 46 adapted to extend through a locking aperture in the wall W, as indicated in Fig. 3. The operating or actuating member 47 for the locking plate 45, Figs. 1, 3 and 9, has prongs 47^a engaging in the apertures 47^b, of plate 45, Fig. 10, whereby the member 45 slides with respect to the member 42 and block 31 under the control of the member 47, which has a movement in the nature of a pivotal movement effected by the engagement of its lugs 47^c loosely in pockets 48, Fig. 3, in member 31. Disposed in a socket 49, Figs. 1, 3 and 12, in the block 31 is a spring 50, embracing the member 47^d on the member 47 and thrusting against the member 47 to hold the locking member 45 in its outward position, indicated in Fig. 12, in engagement with the inturned lugs 44^a on the members 43.

The member 47 has an elongated aperture 47^e, Fig. 9, for loosely embracing the outer end of the tripping rod 39, where it is of reduced diameter, the rod 39 at full diameter forming a shoulder against which the member 47 may thrust when the main-

ber 47 is moved in counter-clockwise direction, as viewed in Figs. 3 and 12, about its pivotal support in the pockets 48, to actuate the tripping lever 34 and therefore 5 through the latches 15 to trip both switches or breaker arms.

As indicated in Figs. 1 and 12, the spring 50 biases the locking member 45 to position in which the block 31 or actuator member 10 is free to be rotated, thereby rotating the member 30 for resetting either or both switches or circuit breakers. If it is desired, however, to lock the resetting member 30 in inoperative or neutral position, in which 15 indicated in Figs. 1 and 2, and to which it is returned by the spring 30^a, Fig. 1, the locking member 45 must be moved to the locking position, where its lug 46 enters the aperture in the wall W, by pressing inwardly 20 upon the member 47, which, however, as it is moved inwardly, moves the tripping rod 39 toward the left, Figs. 1, 3 and 12, tripping such breaker or breakers as may be in the circuit closing position. 25 To retain the actuating member 31 in the locked position indicated in Fig. 3, in opposition to spring 50, there is inserted around the member 44^a of the member 42, secured to the block 31, the hasp 51 of a padlock 30 52, the hasp 51 extending into the path of travel of the locking member 45, preventing its return by spring 50 to unlocking position. A key controls the padlock 52, whose hasp 51, however, directly controls the locking member 45, it being necessary to unlock the padlock 52 and remove the hasp 51 and thereby permit the spring 50 to remove member 45 from locking position to free the actuating member 31 before either or both 35 breakers may be reset or restored to circuit closing position.

In Figs. 15 to 18 inclusive is shown a modified structure wherein the locking member 45 and the lock-actuating member 47 are 40 integral, the member 47 having the aperture 47^t, through which extends the portion of the tripping rod 39 of reduced diameter, the spring 50 in this instance being disposed between the end of the shaft 29 and the member 47, whereby upon pushing inwardly 45 toward the left, Fig. 15, upon the member 47, the tripping rod 39 will be moved to the left to effect the tripping operation, and the locking member 45 will be moved to carry its locking lug 46 into locking position, where it may be held by inserting the hasp 51 of the padlock 52.

In Figs. 19 to 22 inclusive is shown a 50 modification of the structure shown in Figs. 1 to 13 inclusive. In this case the member 47 has at its lower ends the lugs 47^s having pivot holes 47^h, through which extends the pivot pin 47^t, Figs. 19 and 20, whereby the member 47 is pivoted upon the sides 43 of 55 member 42.

In the arrangement indicated in Figs. 23 to 26 inclusive, tripping of the circuit breakers by actuation of the tripping rod 39 does not occur when the locking member 45 is moved to locking position. In this 70 case, the member 45 has a downwardly extending lug 45^a, against which the spring 50 thrusts, the spring 50 being held in position by the lug 45^b. In this instance the actuating member 32 is locked by pressing 75 inwardly upon the member 45^a and then inserting the hasp 51 of the padlock. In this case tripping of the breaker is not effected, but the same may nevertheless be tripped at will either when the member 80 32 is locked or unlocked, by pressing inwardly upon the button 40.

The switching or circuit breaker mechanism of the character hereinbefore described, comprising a base carrying the switching mechanism, and a housing enclosing the switching mechanism, is secured upon a switchboard S, preferably of insulating material, as slate or marble, along with other switchboard devices or instruments, such as 85 90 switching or circuit breaker mechanism, voltmeters, ammeters, etc.

For this purpose the base 1 is secured to the switchboard S and the housing detachably secured either to the base or the switchboard. 95

At the upper end of the base 1 are one or more members 53 lying between and spacing the base 1 and switchboard S, or, if desired, disposed in a depression of either 100 the base 1 or switchboard S. The member 53 may be secured either to the switchboard S or the base 1. In the example illustrated, the screw or bolt 54 extends through the base 1 from its front, and is threaded into 105 the member 53 and extends through the switchboard S and has applied to its rear end the nut 55. The member 53 has its upper end extending forwardly and upwardly, as indicated at 56, to form a hook 110 or pivot received into a correspondingly shaped aperture in the end 57 of the member 58 secured upon the housing H.

By screws or bolts 54 at the lower end of the base 1, extending through it and the 115 switchboard S, the base and switchboard are secured to each other. Here again the screw 54 may be threaded into the member 59 disposed between the base and switchboard, and having secured thereto the lugs or ears 60, in which is pivoted the bail or hasp 61 engaging in the notch 62 of the toggle link 63, pivoted at 64 in the lug or ear 65 carried by the housing H. This fastening is of a character described in my co-pending application 120 Serial No. 619,586, and is in the nature of a toggle as therein described. The link 63 is provided with an aperture 66 adapted to register with a similar aperture in a lug 67 carried by the housing H. The hasp of the 125 130

padlock may be inserted through the registering apertures 66, thereby to effectively lock the housing to the base 1, switchboard 8, or both, the housing 11 carrying on its 5 interior a lug or bracket 68 engaging the base 1.

What I claim is:

1. The combination with an electric switch having a movable contact member and a 10 rotatable actuating member therefor, of a locking member carried by said actuating member and slidable thereon substantially parallel with the axis of rotation of said actuating member, a relatively fixed member 15 engaged by said locking member to lock said actuating member against rotation, and a detachable member carried by said actuating member for holding said locking member in predetermined position.
2. The combination with an electric switch 20 having a movable contact member and a rotatable actuating member therefor, of a locking member carried by said actuating member and slidable thereon substantially parallel with the axis of rotation of said actuating member, a relatively fixed member 25 engaged by said locking member to lock said actuating member against rotation, a spring biasing said locking member to position to 30 free said actuating member, and a member engaging with said actuating member for holding said locking member in locking position in opposition to said spring.
3. The combination with an electric switch 35 having a movable contact member, of a housing enclosing said switch, a member for actuating said movable contact member carried by a wall of said housing and rotatable about an axis substantially normal to said 40 wall, said wall having an aperture, a locking member carried by said actuating member and adapted to engage in said aperture to lock said actuating member, a spring opposing movement of said locking member 45 into said aperture, and a lock having a member engaging with said actuating member and holding said locking member in locking position in opposition to said spring.
4. The combination with an electric switch 50 comprising a movable contact member, an actuating member therefor, and means for restraining said contact member in normal position, of a member for locking said actuating member against movement, and 55 means for actuating said restraining means to trip said movable contact member upon movement of said locking member to position for locking said actuating member.
5. The combination with an electric switch 60 comprising a movable contact member, an actuating member therefor, and means for restraining said contact member in normal position, of a member for locking said actuating member against movement, means 65 for actuating said restraining means to trip

said movable contact member and moving said locking member to predetermined position, and a removable member for holding said locking member in said predetermined position.

6. The combination with an electric switch comprising a movable contact member, an actuating member therefor, and means for restraining said contact member in normal position, of a member for locking said actuating member against movement, means for actuating said restraining means to trip said movable contact member and moving said locking member to predetermined position, and a member forming a part of a lock for holding said locking member in said predetermined position.

7. The combination with an electric switch comprising a movable contact member, an actuating member therefor, and means for restraining said contact member in normal position, of a member for locking said actuating member against movement, means for actuating said restraining means to trip said movable contact member and moving said locking member to position to lock said actuating member against movement, and a removable member for holding said locking member in locking position.

8. The combination with an electric switch comprising a movable contact member, an actuating member therefor, and means for restraining said contact member in normal position, of a member for locking said actuating member against movement, means for actuating said restraining means to trip said movable contact member and moving said locking member to position to lock said actuating member against movement, and a member forming a part of a lock for holding said locking member in locking position.

9. The combination with an electric switch comprising a movable contact member, an actuating member therefor, and means for restraining said contact member in normal position, of a locking member for locking said actuating member against movement, means controlling said restraining means, and a member holding said locking member and said controlling means in predetermined positions.

10. The combination with an electric switch comprising a movable contact member, an actuating member therefor, and means for restraining said contact member in normal position, of a locking member for locking said actuating member against movement, means controlling said restraining means, and a member holding said locking member and said controlling means in positions, respectively, locking said actuating member against movement and preventing restraint of said contact member by said restraining means.

11. The combination with an electric

switch comprising a movable contact member, an actuating member therefor, and means for restraining said contact member in normal position, of a locking member for locking said actuating member against movement, means controlling said restraining means, and a member holding said locking member and said controlling means in predetermined positions, said last named member forming a part of a removable lock.

12. The combination with an electric switch comprising a movable contact member, an actuating member therefor, and means for restraining said contact member in normal position, of a locking member for locking said actuating member against movement, means controlling said restraining means, and a member holding said locking member and said controlling means in positions, respectively, locking said actuating member against movement and preventing restraint of said contact member by said restraining means, said last named member forming a part of a removable lock.

13. The combination with an electric switch having a movable contact member and an actuating member therefor, of a locking member carried by said actuating member for locking it against movement, a member engaging said actuating member for holding said locking member in a predetermined position, and a lock carried by said actuating member for preventing removal of said last named member.

14. The combination with an electric switch comprising a movable contact member, an actuating member therefor, and means for restraining said contact member in normal position, of a locking member carried by said actuating member for locking it against movement, means carried by said actuating member for actuating said restraining means to trip said movable contact member and for moving said locking member to predetermined position, and a removable member for holding said locking member in said predetermined position.

15. The combination with an electric switch comprising a movable contact member, an actuating member therefor, and means for restraining said contact member in normal position, of a locking member carried by said actuating member for locking it against movement, means carried by said actuating member for actuating said restraining means to trip said movable contact member and for moving said locking member to predetermined position, a removable member for holding said locking member in said predetermined position, and a lock carried by said actuating member and of which said last named member is a part.

16. The combination with an electric switch comprising a movable contact member, and means for restraining it in normal

position, of a rotatable shaft, an actuating member secured thereto for actuating said movable contact member, a tripping rod movable through said shaft for actuating said restraining means, a locking member carried by said actuating member for locking it against movement, and a member carried by said actuating member for actuating said tripping rod and said locking member.

17. The combination with an electric switch comprising a movable contact member, and means for restraining it in normal position, of a rotatable shaft, an actuating member secured thereto for actuating said movable contact member, a tripping rod movable through said shaft for actuating said restraining means, a locking member carried by said actuating member for locking it against movement, a member carried by said actuating member for actuating said tripping rod and said locking member, and a lock carried by said actuating member for holding said locking member in predetermined position.

18. The combination with an electric switch comprising a movable contact member, an operating member therefor, means for restraining said contact member in normal position, and electro-responsive means for actuating said restraining means, of a housing enclosing the same, a resetting member carried by said housing in detached relation to said operating member for actuating it, an actuating member on the exterior of said housing for actuating said resetting member, a locking member carried by said actuating member for engaging said housing to lock said actuating member in position in which it is free of said operating member upon actuation of said restraining means by said electro-responsive means, and a member carried by said actuating member for holding said locking member in predetermined position.

19. The combination with an electric switch comprising a movable contact member, an operating member therefor, means for restraining said contact member in normal position, and electro-responsive means for actuating said restraining means, of a housing enclosing the same, a resetting member carried by said housing in detached relation to said operating member for actuating it, an actuating member on the exterior of said housing for actuating said resetting member, a locking member carried by said actuating member for engaging said housing to lock said actuating member, in position in which it is free of said operating member upon actuation of said restraining means by said electro-responsive means for actuating said restraining means, a spring biasing said locking member to position leaving said actuating member free to move, and a removable member carried by said actu-

ating member for holding said locking member in locking position in opposition to said spring.

20. The combination with switching mechanism comprising a movable contact member, an operating member therefor, and means for restraining said contact member in normal position, of a housing enclosing said switching mechanism, a resetting member carried by said housing in detached relation to said operating member for operating it, a tripping member carried by said housing for actuating said restraining means to trip said contact member, an actuating member on the exterior of said housing for actuating said resetting member, a locking member for locking said actuating member against movement, and a member carried by said actuating member for actuating said tripping member and said locking member.

21. The combination with switching mechanism comprising a movable contact member, an operating member therefor, and means for restraining said contact member in normal position, of a housing enclosing said switching mechanism, a resetting member carried by said housing in detached relation to said operating member for operating it, a tripping member carried by said housing for actuating said restraining means to trip said contact member, an actuating member on the exterior of said housing for actuating said resetting member, a locking member for locking said actuating member against movement, a member carried by said actuating member for actuating said tripping member and said locking member, and a removable member of a lock holding said locking member in predetermined position.

22. The combination with an electric switch having a movable contact member, means for restraining said contact member in normal position, and a detached rotatable actuating member for resetting said contact member to normal position after actuation of said restraining means, of a relatively fixed member, and a locking member mounted upon and movable with respect to said actuating member and engaging said fixed member to lock said actuating member when said actuating member has been moved to inoperative position.

23. The combination with an electric switch having a movable contact member, means for restraining said contact member in normal position, a detached actuating member rotatable from an inoperative position for resetting said contact member to normal position after actuation of said restraining means, and a spring biasing said actuating member toward said inoperative position, of a relatively fixed member, and a locking member mounted upon and movable with

respect to said actuating member and engaging said fixed member to lock said actuating member when said actuating member has been moved to said inoperative position.

24. The combination with an electric switch having a movable contact member and a rotatable actuating member therefor, of a relatively fixed member, a locking member carried by said actuating member and slidable thereon towards said fixed member in a path substantially parallel with the axis of rotation of said actuating member, and a member carried by said actuating member on the opposite side of said axis of rotation from said locking member and extending to and engaging said locking member for actuating it.

25. The combination with electric switching mechanism comprising a plurality of independently operable contact members, means for restraining them in normal position, and a resetting member detached from said contact members and rotatable to positions for resetting said contact members successively after actuation of said restraining means, of a housing enclosing said switching mechanism and carrying said resetting member, a locking member carried by said resetting member and adapted to engage said housing when said resetting member is moved to position inoperative with respect to said contact members, a spring biasing said locking member towards position to free said resetting member, and a second locking member engaging with said resetting member for holding said first named locking member in locking position in opposition to said spring.

26. The combination with an electric switch having a movable contact member, a detached actuating member therefor, means for restraining said contact member in normal position, and electro-responsive means for actuating said restraining means, of a locking member for locking said actuating member in position in which said contact member may move independently of said actuating member upon actuation of said restraining means by said electro-responsive means, a spring biasing said locking member toward position for unlocking said actuating member, and a lock for holding said locking member in locking position in opposition to said spring.

27. The combination with an electric switch having a movable contact member, a detached movable actuating member thereof, means for restraining said contact member in normal position, and electro-responsive means for actuating said restraining means, of a locking member movable with said actuating member for locking it in position in which said contact member may move independently of said actuating member upon actuation of said

restraining means by said electro-responsive means, a spring biasing said locking member toward position to unlock said actuating member, and a lock for locking said locking member in locking position in opposition to said spring.

28. The combination with an electric switch having a movable contact member; a detached movable actuating member therefor, means for restraining said contact member in normal position, and electro-responsive means for actuating said restraining means, of a locking member movable with said actuating member for locking it in position in which said contact member may move independently of said actuating member upon actuation of said restraining means by said electro-responsive means, a spring biasing said locking member toward position to unlock said actuating member, and a lock engaging with said actuating member for holding said locking member in locking position in opposition to said spring.

29. The combination with an electric switch comprising a movable contact member, an actuating member therefor, and means for restraining said contact member in normal position, of a member for locking said actuating member against movement, means for actuating said restraining means to trip said movable contact member, and means for simultaneously moving said locking member and said last named means.

30. The combination with an electric switch comprising a movable contact member, an actuating member therefor, and means for restraining said contact member in normal position, of a member movable with said actuating member for locking said actuating member against movement, means for actuating said restraining means to trip said movable contact member, and means for simultaneously moving said locking member and said last named means.

31. The combination with an electric switch comprising a movable contact member, an actuating member therefor, and means for restraining said contact member in normal position, of a member carried by said actuating member for locking said actuating member against movement, means for actuating said restraining means to trip said movable contact member, means for simultaneously moving said locking member and said last named means, and a member for holding said locking member in locking position.

32. The combination with an electric switch comprising a movable contact member, an actuating member therefor, and means for restraining said contact member in normal position, of a member carried by said actuating member for locking said ac-

tuating member against movement, means for actuating said restraining means to trip said movable contact member, means for simultaneously moving said locking member and said last named means, and a member engaging said actuating member for holding said locking member in locking position. 70

33. The combination with an electric switch comprising a movable contact member, an actuating member therefor, and means for restraining said contact member in normal position, of a member for locking said actuating member against movement, and means common to said locking member and said restraining means for actuating them. 75

34. The combination with electric switching mechanism comprising a movable contact member and means for restraining it in normal position, of an enclosing housing, a rotatable actuating member carried by a wall of said housing and disposed in detached relation to said contact member for resetting it after it is freed from said restraining means, a locking member for locking said actuating member with respect to said housing, means for holding said locking member in locking position, and means causing said contact member to be freed 85 from said restraining means before said holding means holds said locking member in locking position. 90

35. The combination with an electric switch comprising a movable contact member, an actuating member therefor, and means for restraining said contact member in normal position, of a member for locking said actuating member against movement, and means common to said restraining 100 means and said locking member for actuating them in succession. 105

36. The combination with an electric switch comprising a movable contact member, an actuating member therefor, and means for restraining said contact member in normal position, of a member for locking said actuating member against movement, and means for actuating said restraining 110 means to trip said contact member and thereafter bring said locking member to position for locking said actuating member. 115

37. The combination with an electric switch comprising a movable contact member, a rotatable actuating member therefor, and means for restraining said contact member in normal position, of a member mounted upon and movable with respect to said actuating member for locking it against movement, and a member extending 120 through said actuating member and movable in a direction parallel with its axis of rotation for actuating said restraining means. 125

38. The combination with an electric 130

switch comprising a movable contact member, a rotatable actuating member therefor, and means for restraining said contact member in normal position, of a relatively fixed member, a locking member carried by said actuating member and pivotally movable with respect thereto on one side of the axis of rotation of said actuating member, said locking member engaging said fixed

member on the opposite side of said axis ¹⁰ of rotation, and means for actuating said restraining means to trip said movable contact member upon movement of said locking member to position for locking said actuating member.

WILLIAM M. SCOTT.

Certificate of Correction.

It is hereby certified that in Letters Patent No. 1,597,832, granted August 31, 1926, upon the application of William M. Scott, of Tredyffrin Township, Chester County, Pennsylvania, for an improvement in "Switching Apparatus," errors appear in the printed specification requiring correction as follows: Page 4, line 19, claim 1, after the word "in" insert the article "a"; page 5, lines 126 and 127, claim 19, strike out the words "for actuating said restraining means"; page 6, line 123, claim 27, for the word "thereof" read *therefor*; and that the said Letters Patent should be read with these corrections therein that the same may conform to the record of the case in the Patent Office.

Signed and sealed this 30th day of November, A. D. 1926.

[SEAL.]

M. J. MOORE,
Acting Commissioner of Patents.
